APPARATUS FOR STORING AND DISPENSING LIQUEFIED HYDROCARBON GAS

David J. Little, San Antonio, Tex., assignor to
Southern Steel Company, a corporation of
Texas

Application April 12, 1937, Serial No. 136,490

8 Claims. (Cl. 62—1)

This invention relates to apparatus for storing and dispensing volatile hydrocarbon gas and, among other objects, aims to provide a simple and inexpensive system adapted to supply hydrocarbon gas for domestic and commercial use. The main idea is to provide a reliable, safe and economical system for generating gas from butane, propane and other highly volatile liquefied gases or fuel mixtures. A further aim is to provide an underground pressure system wherein some of the heat of vaporization or gasification is supplied by the earth to the tank and relatively warm water is discharged above the tank and the service conduit to supply additional heat, which insures a continuous supply of gas and revaporizes any condensate in the service conduit.

Other aims and advantages of the invention will appear in the specification, when considered in connection with the accompanying drawing, wherein:

Fig. 1 is a side elevation, partly in section, showing a system embodying the invention;

Fig. 2 is a similar view showing a slightly modified form of the invention; and

Fig. 3 is a sectional view taken on the line 3—3 of Fig. 2.

Referring particularly to the drawing, a pressure storage tank 10, partially filled with the liquefied gas, is shown in Fig. 1 as being buried in the earth below the frost line. It is placed in a pit and surrounded by porous heat conducting material 11 such as wet sand or the like, so that it may absorb some heat from the earth to vaporize the liquid.

A discharge conduit 12 is connected to the tank and is shown as extending above the ground level. A cut-off valve 13 and an ordinary pressure regulator 14 are connected to the conduit above the ground, where they are easily accessible, it being understood that they may be housed in a suitable protecting cover (not shown). A tee 15 having a filling plug 16 is provided in the conduit below the pressure regulator so that the filling hose of a service tank hose may be connected to it. The tank also has a vent pipe 17 carrying a valve 18 and a vent plug 19 above the valve to permit the gas receiving or vent hose of a service tank to be connected to the vent pipe. A slip-tube gage 20 like that shown in my copending application, Ser. No. 136,489, filed April 12, 1937, is adapted to be lowered through the bent pipe past the valve 18 to determine the level in the tank. It is contemplated, however, that an ordinary float operated gage may be employed. The arrangement is such that the storage tank may be con-

nected in a closed circuit to a service tank, as explained in my aforesaid application. When the storage tank is filled to the desired level, the valves 13 and 19 are closed, the service tank hoses removed and the plugs 16 and 19 replaced. Then, the valve 13 is again opened.

A service main 21 is connected to the low pressure side of the regulator and is shown as projecting downwardly into the ground to a point near the level of the storage tank 10 below the frost line. It has a cut-off valve 22 which may be closed during the filling operation. A horizontal run or length of pipe 23 extends immediately above and parallel with the tank. This portion of the main is utilized as a heat exchanger to revaporize any condensed gas in the service main. In this instance, a small water spray pipe 24 is connected to discharge water above and throughout substantially the length of the pipe 23 so that the water will come in contact with the pipe and also trickle through the earth fill or sand around the storage tank 10, thereby providing additional heat for vaporizing the liquefied gas in the tank. This additional heat is sometimes very necessary, especially during cold weather, to supply some of the latent heat of vaporization of the liquefied gas. If desired, the water may be drained from the bottom of the tank pit by an ordinary drain pipe 25. Thus, a constant supply of gas is assured in the coldest climates. It is contemplated that the water may be cut off during hot weather or in hot climates. The length or portion 23 of the service main is arranged at the lowest level thereof so that any condensed gas will flow to it and be revaporized.

In Figs. 2 and 3, there is shown a slightly modified form wherein the tank 10' is placed in a concrete vault 30 in the form of a rectangular box having cover slabs or boards 31 and the service pipe 23' extends longitudinally through the upper portion of the vault above the tank in the same manner as explained in connection with Fig. 1. The water spray pipe 24' is arranged above the service main to spray the water on it and permit the water to drain downwardly on top of the storage tank. The used water may be drained through an outlet conduit 25' connected to the bottom portion of the concrete box. The concrete vault is preferably built in the ground below the frost line, as in Fig. 1, so that the water in the spray pipe will not freeze in cold climates. In this case, the air in the vault is heated by the surrounding earth and serves as a natural heating medium for the tank. The heat supply is augmented by the water sprayed on the tank.

From the foregoing description, it will be seen that the improved system is extremely simple in its design and reliable in operation. It may be manufactured and installed at a very low cost and has no complicated or delicate parts which require frequent attention or replacement. It is well adapted for household and commercial installations.

Obviously, the present invention is not restricted to the particular embodiment thereof herein shown and described. Moreover, it is not indispensable that all the features of the invention be used conjointly, since they may be employed advantageously in various combinations and sub-combinations.

What is claimed is:

1. In a liquefied gas dispensing system of the class described, an underground storage tank; a gas discharge conduit connected to the tank; a pressure regulator connected to said conduit; a service main connected to the pressure regulator and having a portion located above and adjacent to the top of the tank; and a pipe connected to discharge relatively warm water in heat exchanging relation to said portion of the service main and said tank to revaporize condensed gas in the service pipe and also supply additional heat to the tank.
2. In a liquefied gas dispensing system of the class described, an underground storage tank; a gas discharge conduit connected to the tank; a pressure regulator connected to said conduit; a service main connected to the pressure regulator and having a portion located above and adjacent to the top of the tank; and means for supplying relatively warm water to heat said portion of the gas main and also supply heat to said tank.
3. In a liquefied gas storage and dispensing system of the class described, a pressure storage tank buried in a pit below the frost line; porous heat conducting filler material surrounding the tank; a gas dispensing conduit connected to the tank and having a portion buried in the porous filler material above the tank; and means to deliver relatively warm water through the filler material so that it comes in heating contact with said dispensing pipe and tank.
4. In a liquefied gas storage and dispensing

system of the class described, a pressure storage tank buried in a pit below the frost line; porous heat conducting filler material surrounding the tank; a gas dispensing conduit connected to the tank and extending above the ground level; a pressure regulator connected to the dispensing conduit; a service main leading from the regulator back into the ground and having a portion buried in the filler material above the tank; and a water spray pipe also buried in the filler material above the service main and tank to discharge water so that it will supply heat to the lowest portion of the main and to the tank.

5. In a liquefied gas storage and dispensing system of the class described, a pressure storage tank buried in a pit below the frost line; porous, heat conducting filler material surrounding the tank; a gas dispensing conduit connected to the tank; and means to deliver running water through the porous filler in heating contact with the tank.

6. In a liquefied gas storage and dispensing system of the class described, a vault buried underground below the frost line; a storage tank in the vault; a gas dispensing conduit and main connected to the tank and having a portion in said vault above the tank; a water spray pipe above said portion of the conduit within the vault to discharge water to heat it and said tank; and a drain connected to said vault.

7. In a liquefied gas storage and dispensing system of the class described, a vault buried underground below the frost line; a storage tank in the vault; a gas dispensing conduit and main connected to the tank and having a portion in said vault above the tank; and means to deliver running water through the vault in heating contact with said conduit and tank.

8. In a liquefied gas storage and dispensing system of the class described, a vault buried underground below the frost line; a storage tank in the vault; a gas dispensing conduit and main connected to the tank and having a portion in said vault above the tank; and means to deliver running water through the vault in heating contact with the outside wall of the tank.
